Des 832

9-16-1856

Dec 832

Antoine Glomisiski of Lansingburgh, N. Y.

Assignor to

D. A. E. & N. R. Powers of the same place.

Letters Patent No. 832, Dated Sept, 16th 1836.

The schedule referred to in these Letters Patent, and making part of the same.

To all whom it may concern:

Be it known that I, Antoine Glomisiski of Lansingburgh, in the County of Rensselaer, and State of New York, have invented and produced a new design, pattern, or figure to be printed, stamped or used upon Floor Oil Cloths or other fabrics, and I do hereby declare that the following is a full and exact description of the same, viz.

The pattern is divided into two squares; and two octagons, each of unequal adjoining sides, by coloring so arranged as to appear like a rounded moulding carved with Arabesque figures - These squares and octagons, are fully shown when the pattern is repeated.

In the centre of each octagon is placed a figure representing a group of leaves, upon a ground of different color from the remainder of the pattern.

This ground is surrounded by a moulding with a flat border broken into sections by lines of lighter color, and separated from the rounded moulding by a plain ground of the same tint as one used in the moulding.

In the centre of each square is placed a rosette surrounded by a similar moulding, band, and ground to those last described.

And what is claimed as my invention and desired to be secured by Letters Patent of the United States, is the arrangement of ornamental figures forming a design for Floor Oil Cloths or other fabrics, as shown in the aforesaid drawings.
